INVENTOR
William H. Wallace
BY
Frederick C. Fischer
ATTORNEY

UNITED STATES PATENT OFFICE.

WILLIAM H. WALLACE, OF NEWARK, NEW JERSEY.

SPARK-PLUG CLEANER, TESTER, AND ADJUSTER.

1,345,721.

Specification of Letters Patent.

Patented July 6, 1920.

Application filed June 24, 1919. Serial No. 306,474.

To all whom it may concern:

Be it known that I, WILLIAM H. WALLACE, a citizen of the United States, residing in the city of Newark, county of Essex, and State of New Jersey, have invented certain new and useful Improvements in Spark-Plug Cleaners, Testers, and Adjusters, of which the following is a full, clear, and exact description, such as will enable others skilled in the art to which it pertains to make, construct, and use the same, reference being had to the accompanying drawings, and to numerals of reference marked thereon, forming a part of this specification.

The present invention relates to spark-plug cleaners, testers, and adjusters, of a type adapted for carrying in the pocket or in a tool-box.

As is well known the electrodes of spark-plugs from constant use become covered with carbon, and also the annular cavity of the spark-plug casing surrounding the said electrodes, and the effective spark-gap between the electrodes becomes changed thereby producing an inoperative or poorly operating spark-plug.

In order to remove the carbon from the electrodes and to properly adjust the same, it has heretofore been common to employ any handy tool or device which was available, such as, for instance, an ordinary pen-knife, screw-driver, or a file.

It is an object of the present invention, to provide a device of exceedingly simple, efficient and inexpensive construction which can be conveniently carried in the pocket or tool-box, and by the use of which a fouled spark-plug can be readily freed from carbon, the electrodes thereof brightened and properly adjusted, and the spark-plug tested.

My present invention therefore consists in the novel construction of a spark-plug cleaner, tester and adjuster embodying the principles herein above mentioned, and of a character to be more fully described in the following specification. This invention consists furthermore in the several novel arrangements and combinations of the various parts, as well as in the details of construction of the same, all of which will be hereinafter more fully set forth and then finally embodied in the clauses of the claim which are appended to this specification.

The invention is fully illustrated in the accompanying drawings, in which—

Figure 1 represents a side elevation of a spark-plug, partly in section, illustrating my improved device, in dotted lines, applied to the plug for testing the same;

Figs. 2, 3 and 4 represent, respectively, front, top and rear views of my improved device; and

Fig. 5 represents a transverse sectional view, on an enlarged scale, taken on line *x-x* of Fig. 2.

Similar numerals of reference indicate corresponding parts throughout the specification and drawings.

So far as the general construction of the plug is concerned, it may be of any desired form or construction.

In the accompanying drawings my improved device is represented as consisting of a metallic blade 1 and a non-conductive handle 2 of any suitable material, preferably wood, secured thereto.

The metallic blade is hardened and in its preferred form is of rectangular cross-section, the longitudinal edge 3 and the end edge 4 of the front thereof being beveled to provide a scraping or cutting surface.

The front surface of the blade is further provided with a filing surface as at 5.

The rear surface of the blade near the front edge thereof is formed with a recessed or cutaway portion 6, so as to provide a suitable gage on the device having a thickness corresponding with the proper width of the spark-gap, and which is intended to be inserted between the electrodes of the plug, whereby the distance therebetween may at all times be properly adjusted.

It will thus be seen that by the employment of the file 5, all carbon can be removed from the electrodes and the same can be brightened; by the employment of the cutting or scraping surface formed on the longitudinal edge 3, the annular cavity of the spark-plug casing can be freed from carbon; and by the employment of the cutting or scraping surface formed on the end edge 4 of the blade the front of the casing can be scraped; and further by the employment of the recessed or cutaway portion 6 of the device which is inserted between the electrodes, the spark-gap may be properly adjusted.

As illustrated in Fig. 1 of the drawings, if the device is employed as therein indi-

cated, a proper test of the spark-plug can be made.

Experience has demonstrated that the organization above described, is a highly efficient one, and while I have shown the preferred embodiment of my invention, I do not care to be limited to the exact structure shown and described, as minor variations thereof may be made by anyone skilled in the art. It is, of course, to be understood that this device can be effectively used for filing, brightening, and spacing the contact points on coils, etc.

I claim:—

15 1. A device of the character described, consisting of a straight metallic blade, a non-conductive handle therefor, said blade being provided with a longitudinal and a transverse scraping edge, a filing surface

arranged upon one of the longitudinal sides 20 of said blade, and a recessed reduced spacing portion arranged on the opposite side and near one end thereof.

2. A device of the character described, consisting of a straight metallic blade, said 25 blade being provided with a longitudinal and a transverse scraping edge, a filing surface arranged upon one side of said blade, and a recessed reduced spacing portion arranged on the opposite side and near one 30 end thereof.

This specification signed and witnessed this 23d day of June, 1919.

WILLIAM H. WALLACE.
